[57] CLAIM

The ornamental design for a toothbrush handle, as shown and described.

DESCRIPTION

FIG. 1 is a perspective view;
FIG. 2 is a top view from directly on top;
FIG. 3 is a front elevation view from the very front;
FIG. 4 is a rear elevation view from the back;
FIG. 5 is a right side view;
FIG. 6 is a left side view; and,
FIG. 7 is a bottom view from upside down.
The broken lines showing bristles and a mounting base are for illustrative purposes only and form no part of the claimed design.
